UNITED STATES PATENT OFFICE.

LUCIEN B. WOOLFOLK, OF LEXINGTON, KENTUCKY.

IMPROVEMENT IN SELF-FEEDING STOVES.

Specification forming part of Letters Patent No. 172,817, dated January 25, 1876; application filed February 15, 1875.

To all whom it may concern:

Be it known that I, LUCIEN B. WOOLFOLK, of Lexington, in the county of Fayette and State of Kentucky, have invented a new and useful Improvement in Self-Feeding Stoves, of which the following is a specification:

My invention consists, first, in constructing a chamber at the top of the stove with inlet and outlet, for receiving and discharging into the smoke-escape any gas leaking around the valve-plate; secondly, in an improved construction of the magazine, by which a regular and sufficient supply of fuel for all weathers is fed to the grate, and for preventing the passage through the magazine of any draft; thirdly, in an improvement in the construction of the grate for securing a radiant heat; fourthly, in improvements in the grate-bottom, and parts connected therewith, for regulating the draft.

Figure 1 is a vertical section taken through the center of the stove. Fig. 2 is a horizontal section taken through the line 1 2 of Fig. 1. Fig. 3 is a horizontal section taken through the line 3 4 of Fig. 1. Fig. 4 is a side elevation of the stove. Fig. 5 is a plan view of the ash-plate and the supporting-plate upon which it rests, showing the slot and hole by which the ash-plate is moved. Fig. 6 is a vertical section of the upper part of the stove, taken through the center, showing a modification of the arrangement of the gas-chamber, constructed above the valve-plate that closes the magazine-pipe. Fig. 7 is a vertical section of the same, taken through the center, showing another modification of the gas-chamber.

A is the outer case of the stove, consisting of the several sections A¹ A² A³ A⁴ A⁵.

B is the magazine-pipe for containing fuel. It is attached air-tight to a downward-projection of the top section A⁵, and is a solid pipe, without any outlet to admit of the escape of gas, or cause a draft through the fuel in the magazine. The magazine-pipe is widened from the top downward, extending considerably from the part c¹ c¹ to the bottom c² c², which is made flaring. The advantages of this construction are as follows: It is capable of containing a large quantity of fuel, which it feeds down very readily, and by its wide mouth furnishes a constant and ample supply to the grate at all times.

I construct, additionally, a gas-chamber, A⁶, in a separate section at the top piece of the stove, for the purposes hereinafter mentioned.

C is the burner, attached to the bottom of the magazine-pipe, with the joint either open or made tight with cement. The burner C is narrowed toward the bottom, for the purpose of sustaining the fuel in the magazine. It is constructed with grate-bars or fingers, the better to induce the combustion of the fuel it contains.

E is a valve-plate, fitting air-tight, which closes the top of the magazine-pipe and prevents any draft therethrough.

A⁶ is a gas-chamber constructed above the valve-plate E, for the purpose of catching the gas escaping from the magazine-pipe around the valve-plate E. The top of the gas-chamber A⁶ is covered by the valve-plate G. On one side of this gas-chamber A⁶ is an air-inlet passage, a, while on the other side is the outlet b, through which the gas passes to the smoke-passage I.

The essential features of my invention are the solid magazine-pipe B, attached to the top section of the stove A⁵ by an air-tight joint, and closed at the top by the valve-plate E, which prevents the circulation of any draft through the magazine. The gas will thus leak around the valve-plate E. To catch this gas and prevent its entering the room where the stove stands, I construct the chamber A⁶ above said valve-plate, having an inlet-passage, a, and an outlet-passage b, which latter communicates with the smoke-escape.

The various parts of my present invention may be variously modified in detail without departing from the true principles thereof. The smoke-escape I may pass either through the top of the stove, as in Figs. 1, 2, 4, and 6, or it may pass through the side of the stove.

L L are the lower doors of the stove, working upon hinges M. These doors are provided with sashes, into which are fitted mica plates. Upon these doors L are ears N, and a hole for enabling said doors to be opened by a hook or other means.

L' L' are the upper doors, fitted up and worked in like manner.

O is the grate, resting at the top upon an inward projection of the stove. At the point of attachment are fluted grooves for the pas-

sage of air between the grate and the stove, the better to promote the consumption of the gas in the fuel. The bars of the grate extend high up toward the top of grate, which is wider at the top than at the bottom, by reason of said bars converging from the top downward.

This arrangement allows of the emission of a radiant heat through the large lower doors of the stove, and also allows the air to pass through the bars, as well as through the fluted air-passages around the grate, instead of through the fuel from the bottom.

P is the grate-bottom, having a hole through which the ashes and cinders fall. The grate-bottom P rests upon the collar Q, which is supported by the arms R.

Beneath the grate-bottom P is the ash-plate S, which is worked back and forth by the pin c, attached to the grate-bottom P, and fitting into the hole d on one side of the ash-plate, as shown in Fig. 5.

To allow of the free movement of the ash-plate by the shaking of the grate-bottom P it is pivoted in a slot, e, in the supporting-plate T.

The hole d is placed on one side of the ash-plate S, in order that the movement of the grate-bottom P may remove the ash-plate entirely from beneath the hole in the grate-bottom.

The ash-plate would work as well as if the hole d were slotted.

I prefer to place the slot in the supporting-plate J only, because it is less liable to be obstructed with ashes.

The hole d might be placed in the middle of the ash-plate instead of on one side.

This arrangement, however, is not of such advantage as that previously described, and shown at Fig. 5, inasmuch as the ash-plate could not be so readily removed from beneath the hole in the bottom of the grate-bottom P.

The grate is agitated by an iron rod passed through a slotted hole, V, into the hole f in the grate-bottom P.

The slotted hole V is closed by the segment U, which is provided with a hole, through which the rod may pass. The rod is hook-shaped at one end, for use in opening the doors and for removing the valve-plate E.

One great advantage of my improvement is the closing of the magazine-pipe, so as to exclude all drafts therefrom.

In the ordinary methods of construction holes are left therein for the escape of gas. Through these outlets a continual draft is created from the fire through the magazine-pipe B, thus carrying off a considerable portion of the heat, and causing a large consumption of fuel without advantage.

This draft through the magazine-pipe in-

volves many disadvantages. It necessitates the contraction of the size of the pipe, which, in turn, feeds to the grate a supply of coal from its narrow mouth insufficient for cold weather. Then, when more coal is raked out, not being pressed downward by the flow from the magazine, it accumulates and forms clinkers, which become very troublesome, and finally extinguish the fire.

By making the magazine-pipe gas-tight and covering the top, so as to stop all draft therethrough, it may be so far enlarged as to contain an ample supply of fuel, and have the mouth large enough to feed it into the grate in sufficient quantity, and keep the clinkers pressed downward toward the bottom of the grate, where they may be regularly discharged without embarrassing the grate. At the same time no heat ascends the magazine-pipe. All the heat arising from the combustion of the fuel passes outside the pipe, and is utilized for heating the room.

This construction I am enabled to adopt with such improved results by constructing the gas-chamber A⁶ with its gas-outlet b above the valve-plate E, through which the gas escaping around the valve-plate E passes into the smoke-passage I.

I am aware that magazine-pipes have heretofore been constructed with a gradual enlargement from the top; and I am also aware that fire-pots have been constructed with grate-bars, or extending downward, and contracted at the bottom. I therefore lay no claim to either arrangement, broadly considered.

The following is claimed as new:

1. The combination, with the grate O, having grate-bars extending very high up, and gradually spreading outwardly from the bottom, where they are narrower than at top, of the grate-bottom P, pin c, ash-plate S, hole d, supporting-plate T, and slot e, substantially as set forth.

2. The combination, with the grate-bottom P, of the ash-plate S, pivoted in the slot e in the supporting-plate T, and worked by the pin c, in the manner set forth.

3. The burner C, contracted toward the bottom, and having fingers to promote combustion, in combination with the magazine-pipe B, expanding from the top down to point c¹, and having the flare c² at bottom, and the top section A⁵, substantially as set forth.

4. The combination of the magazine-pipe B and section A⁶, having air-inlet a and gas-outlet b, constructed and arranged substantially as set forth.

L. B. WOOLFOLK.
